UNITED STATES PATENT OFFICE.

HENRY M. CRIPPEN, OF ATHENS, OHIO, ASSIGNOR OF ONE-FOURTH TO FRED H. FINSTERWALD AND C. A. FINSTERWALD, BOTH OF AKRON, OHIO.

PUMP.

Application filed August 18, 1923. Serial No. 658,084.

To all whom it may concern:

Be it known that I, HENRY M. CRIPPEN, a citizen of the United States, residing at Athens, in the county of Athens and State of Ohio, have invented certain new and useful Improvements in Pumps, of which the following is a specification.

My invention relates to pumps.

The object of the invention is to avoid the use of cup leathers, in the use of which there is so much pressure on the cylinder wall as to quickly wear out such form of packing, and to substitute a construction of piston in which an ordinary flat packing strip or ring may be employed, and in which pressure will be exerted against the packing to force it in proper contact with the cylinder wall during the compression stroke, and the suction stroke of the piston, causing a release of such pressure and permitting a free flow of fluid past the piston to again fill the cylinder.

These objects I accomplish by the construction shown in the accompanying drawing, in which:

Fig. 1 shows in vertical section a pump having my improvements applied thereto; the piston being at the end of the compression stroke.

Fig. 2 is a plan view of the handle and hose retainer.

Fig. 3 is an enlarged sectional view of the upper end of the cylinder, showing the position of the piston elements as they near the end of the suction or up stroke.

Fig. 4 shows a similar view with the parts in the position they occupy at the completion of the up stroke and beginning of the compression or down stroke.

Figs. 5 and 6 are sectional views of a modified form of piston; Fig. 5 showing the parts in the compression stroke and Fig. 6 with the parts in the up or suction stroke.

Fig. 7 shows the packing strip.

The pump illustrated is shown as an ordinary air or tire inflating pump comprising a cylinder 1, foot base 2 having a hose nipple 3 provided with a suitable inwardly closing ball check valve 4, cap piece 5 and hose 6 provided with a suitable nozzle 6'.

These parts are of the usual or any approved construction and may be adapted for air, water or other fluid.

The piston proper 10 has an annular tapered shoulder 11 around its lower outer

edge, forming a seat for the lower edge of a packing strip 16 of leather or other suitable material; the meeting ends of the strip being beveled to nicely fit and form a close joint. The cylindrical body 13 of the piston 60 has a central aperture 12, through which the lower reduced end of the piston rod 20 freely passes. The lower face of the piston 10 is recessed to partially receive a retaining nut 21 on the lower end of the rod 20. The 65 piston 10 is further provided with one or more air passages or openings 22' extending vertically through it from its lower to its upper face, other air and lubricating ports 25 extending from the upper end of 70 the piston body 13 downwardly and outwardly to the rear face of the packing 16. A valve 14 in the form of an inverted cup is provided at its lower edge with a bevel 15 which, in connection with the beveled 75 shoulder 11, will tend in the down or compression stroke to force packing strip 16 out against the cylinder wall and prevent the air from escaping past the edges of the strip. The upper end of the piston body 13 is of 80 slightly less diameter than the interior of the valve 14 so that the piston body 13 will telescope therein and be held properly and guided at this point. The valve 14 has a central downwardly tapering opening 17 extending through its upper closed end and this tapered opening is adapted to receive a tapered shoulder 22 on the rod 20 at the upper end of its reduced portion. The shoulder 22 wedges into this tapered opening 17 85 on the down stroke of the piston and in so doing closes the said opening and forces down the valve 14 until its beveled edge firmly engages the upper edge of the packing so that no fluid may pass the piston during the effective stroke. When the piston is moved upward on its suction stroke the rod 20 will lift the valve 14, as in Fig. 3, and permit air in the cylinder to rush past the exterior of the said valve under its lower 90 edge and down through opening 22' into the lower end of the cylinder; the packing 16 at this time being free from the compressing action of the beveled portions 15, 11, and so will be relieved of wear. When the piston reaches its extreme up stroke the valve may strike cap 5 and be momentarily released, as in Fig. 4, whereupon the downward movement of rod 20 will force the shoulder 22 into the valve opening 17, which 95 100 105 110

in turn will cause the parts to assume the position shown in Figs. 1 and 3. In such down or pressure stroke air will pass up through opening 22 into the air chamber formed by the interior of valve 14 and through openings 25 and exert outward pressure on the rear face of the packing strip and assist in holding it to the cylinder wall. When the valve 14 is thus released by striking cap 5 the nut 21 will lift piston 10 until packing 16 is forced against bevel 15 and so expand the packing and tighten it against cylinder wall. This is useful in case of the packing becoming contracted or set should the pump remain idle for any length of time.

The conical surfaces 22, 17 will hold the valve 14 strictly parallel with the interior of the cylinder and hold it against any tilting action.

20 It will be understood, of course, that the valve 14 is of less external diameter than the interior of the cylinder so that the air is free to pass in the up or suction stroke and also that the cylinder is open to the atmosphere through the opening in cap 5 or otherwise.

In Figs. 5 and 6 the valve 14 is provided with grooves 28 to allow the free passage of the fluid to and under the lower edge of the 30 valve and thence down through the opening or openings 22', as in Figs. 1 and 2, when the valve is raised on the up stroke, as in Fig. 6. The operation is the same as in Figs. 1, 3 and 4.

35 The lower inner face of valve 14 has a rounded boss 27 and the upper face of the piston body 13 has a corresponding recess 27' to receive this boss and permit the parts to telescope as the packing wears down.

40 It will be noticed that the inner lower face of valve 14 is of less diameter than the lower face of the piston 10 so that there is less pressure on valve 14 during the compression stroke than there is upon the lower 45 end of piston 10, which allows the piston to move up to the lower edge of the packing to close all leak at this point.

I have found that Babbitt metal is a good material for the piston and its valve, 50 and as the piston rod is of steel there will be the proper amount of friction between the conical surfaces 22, 17 to cause the rod to lift the valve as described.

The upper end of the rod 20 is formed as 55 a combined handle and hose retainer 29. The handle has an opening at both sides of the rod and the free end of the hose 6, is passed up through one opening and down through the other, as in Fig. 1, so that the 60 hose is properly secured while the pump is being carried or is in storage. The handle is formed by bending the rod in the form of two loops 30, 30 lying in a horizontal plane with the free end 31 of the loop swaged 65 down, where it joins the upper end of rod

20. A clip 32 embraces the parts at this point. This forms a highly useful improvement, as heretofore the hose has been free to fall around in the way, and this frequently causes the hose and valve 6' to become injured.

What I claim is:

1. In a pump, a piston comprising a cylindrical body having an air opening extending therethrough from its upper to its lower side, a central opening, and an external annular collar or shoulder around its lower end, a piston rod extending at its lower end freely through the said central opening and having means for holding the valve from falling off, a valve on the rod above the piston in the form of an inverted rigid cup with its lower packing-expanding edge spaced from the said annular shoulder; the space between said lower edge of the valve and the said shoulder provided with a packing strip.

2. The combination with a piston rod and a piston having a cylindrical body through which the lower end of the rod freely passes for limited movement; said body having an opening through it to one side of the rod and an external annular shoulder around its lower end, a packing strip around said cylindrical portion, and an inverted cup-shaped valve carried by the rod with its lower edge engaging the upper edge of the packing strip; the valve being constructed for the passage of fluid around and under its lower edge to the piston passage.

3. The combination with a piston rod provided with a reduced lower end having a downward tapered shoulder at the juncture of its two diameters, of a piston mounted freely on the lower end of the rod for limited vertical movement thereon, the said piston having a cylindrical body to receive a packing strip therearound, an external annular shoulder to support the lower edge of said packing and a through fluid passage to one side of the piston rod, and an inverted cup-shaped valve having a tapered opening in its upper closed end to receive the tapered shoulder on the piston rod; the lower edge of the valve adapted to engage the upper edge of the packing in the compression stroke and the valve and piston moving apart on the suction stroke to allow the fluid to pass the lower edge of the valve and pass through the piston passage.

4. The combination with a piston rod, of a piston through which the lower end of the rod freely passes, a nut on the rod below the piston; said piston having a cylindrical body, an external annular tapered shoulder and a through fluid passage, and other passages leading from its upper edge out through its side wall, a packing strip around the cylindrical body with its lower edge resting on said shoulder, and a valve on

120
125
130

the rod over the piston and having an annular beveled edge engaging the upper edge of the packing strip.

5. The combination with a piston rod having a tapered shoulder, of a piston having limited movement on the rod below said shoulder and provided with a through port or passage, and an external annular collar, an inverted cup-like valve telescop-

ing the body of the piston and having a central tapered opening receiving said tapered shoulder; the inner lower face of the valve having a central boss and the upper end of the piston body having a recess to receive said boss.

In testimony whereof I affix my signature.

HENRY M. CRIPPEN.
